(57) CLAIM

We claim the ornamental design of a desk lamp, as shown and described.

DESCRIPTION

FIG. 1 is a left front perspective view of a desk lamp showing our new design;

FIG. 2 is a left back perspective thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left front perspective view of the handset portion of the desk lamp, removed from the desk lamp;

FIG. 10 is a left back perspective thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The handset shown in FIGS. 9–16 is shown removed from the desk lamp for convenience of illustration.

The broken lines in the drawings represent unclaimed subject matter.
